UNITED STATES PATENT OFFICE.

JAMES MASEK, OF CHICAGO, ILLINOIS.

STRING-HOLDER.

1,245,254.

Specification of Letters Patent.

Patented Nov. 6, 1917.

Application filed June 17, 1915. Serial No. 34,635.

To all whom it may concern:

Be it known that I, JAMES MASEK, a citizen of the United States, and a resident of the city of Chicago, county of Cook, and State of Illinois, have invented certain new and useful Improvements in String-Holders, of which the following is a specification.

My invention relates to improvements in string holders and has for its object the provision of an improved construction of this character which facilitates the use of string, twine or the like in wrapping bundles.

The invention consists in the combinations and arrangements of parts hereinafter described and claimed.

The invention will be best understood by reference to the accompanying drawing, forming a part of this specification, and in which,

Figure 1 is a side elevation of a string holder embodying my invention,

Fig. 2, a vertical section of the same,

Fig. 3, a top plan view of the same, and

Fig. 4, a front view of the same.

The preferred form of construction as illustrated in the drawing comprises a suitable standard 5 having a downwardly converging recess 6 in its top. A clamping block 7 shaped to fit recess 6 is pivoted at 8 in standard 5 to swing vertically into and out of said recess. At its free end clamping block 7 carries an upstanding operating arm 9. A string guide opening 10 is passed through clamping block 7 adjacent its pivoted side, a string guide opening 11 is passed through the base of arm 9 and a string guide opening 12 is passed through the upper portion of arm 9 as indicated. A guide eye 13 is arranged over the upper entrance to opening 10 and the string 14 is passed through said eye and each of the openings 10, 11 and 12 as indicated, the string being passed downwardly through opening 10 thence around the base and free edge of clamping block 7 thence rearwardly through opening 11 and upwardly and forwardly through opening 12. Entry slots 15, 16 and 17 are provided leading respectively into the openings 10, 11 and 12 to facilitate the threading of the string therethrough. By this arrangement it will be observed that upward tension on the string 14 in front of arm 9 will cause said arm and clamping block 7 to swing upwardly and rearwardly as indicated in dotted lines in Fig. 1 thus leaving string 14 free to pass freely through the device under such tension. When a sufficient quantity of string has thus been withdrawn the tension on the string is changed to a downward direction which draws the clamping block 7 into the recess 6 thus clamping the string against further withdrawal as will be readily understood. In this situation the string may be severed by breaking or otherwise as desired.

To facilitate the severing of the withdrawn portion of string I provide a knife 18 arranged on the upper end of a plate 19 slidably arranged on the front of standard 5 and secured thereto by means of a screw 20 taken through a slot 21 in said plate. The plate 19 is provided with a stop flange 22 at one upper corner and stop flange 23 at the opposite lower corner embracing the sides of standard 5 to guide the plate 19 in its motion. The screw holes 24 are provided in standard 5 to facilitate securing the same to the top of a counter, table or the like. With this arrangement when it is desired to sever the withdrawn end of the string the same is placed under knife 18 as indicated and upward tension applied thereto. This upward tension serves at first to lift the knife 18 and the plate 19 until the bottom of slot 21 strikes screw 20 when further movement of the knife is prevented and the tension will serve to sever the string, after which the knife falls back to original position thus exposing the severed end of the string and facilitating the withdrawal of the next piece.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the class described comprising a standard having a downwardly converging recess in its top; a clamp adapted to fit said recess and pivoted to swing vertically into and out of said recess; and an upstanding operating arm at the free end of said clamp, there being a string guide

opening passing through said clamp adjacent its pivoted end, a string guide opening passing through a lower portion of said arm and a string guide opening passing through an upper portion of said arm, substantially as described.

2. A device of the class described comprising a standard having a downwardly converging recess in its top; a clamp adapted to fit said recess and pivoted to swing vertically into and out of said recess; an upstanding operating arm at the free end of said clamp, there being a string guide opening passing through said clamp adjacent its pivoted end, a string guide opening passing through a lower portion of said arm and a string guide opening passing through an upper portion of said arm; and a severing knife on said standard adjacent the free end of said clamp, substantially as described.

3. A device of the class described comprising a standard having a downwardly converging recess in its top; a clamp adapted to fit said recess and pivoted to swing vertically into and out of said recess; an upstanding operating arm at the free end of said clamp, there being a string guide opening passing through said clamp adjacent its pivoted end, a string guide opening passing

through a lower portion of said arm and a string guide opening passing through an upper portion of said arm; and there also being entry slots leading into said openings, substantially as described.

4. A device of the class described comprising a standard having a downwardly converging recess in its top; a clamp adapted to fit said recess and pivoted to swing vertically into and out of said recess; an upstanding operating arm at the free end of said clamp, there being a string guide opening passing through said clamp adjacent its pivoted end, a string guide opening passing through a lower portion of said arm and a string guide opening passing through an upper portion of said arm, there also being entry slots leading into said openings; and a severing knife on said standard adjacent the free end of said clamp, substantially as described.

In testimony whereof I have signed my name to this specification in the presence of two subscribing witnesses.

JAMES MASEK.
